UNITED STATES PATENT OFFICE.

ARTHUR J. SHIRCLIFFE, OF NORWOOD, OHIO.

AUTOMATIC FRANKING-MACHINE.

1,340,987.

Specification of Letters Patent.

Patented May 25, 1920.

Application filed July 30, 1917. Serial No. 183,561.

To all whom it may concern:

Be it known that I, ARTHUR J. SHIRCLIFFE, a citizen of the United States, and a resident of Norwood, in the county of Hamilton and 5 State of Ohio, have invented a certain new and useful Improvement in Automatic Franking-Machines, of which the following is a specification.

The present invention relates to wood-10 working machines, and more particularly to that type of machine for franking or mortising pieces of work used in the construction of sashes, doors and the like.

In the manufacture of a large percentage 15 of certain kinds of sash, window and door-work, small lengths of various sizes and numbers are required, and this necessitates the punching or forming of small mortises of various sizes and depths in the stiles and 20 rails of the work.

It is an object of the present invention to provide a machine which will accurately, and with great speed, perform the work of punching mortises of the required size; 25 which will reduce the labor cost in operation; which may be quickly adjusted for different sizes and numbers of mortises required; which may be used in conjunction with other machines, such as a sticker, to 30 receive the pieces of work therefrom and which have been prepared to receive the same in the usual manner; which is automatic in operation; which may be operated by inexperienced laborers; and which may 35 operate upon a single piece of work to simultaneously frank or form mortises of various sizes therein.

The above, and various other objects and 40 advantages of this invention will be in part described, and in part understood, from the following detailed description of the present preferred embodiment, the same being illustrated in the accompanying drawings wherein:

45 Figure 1 is a side elevation of a franking machine constructed according to the present invention.

Fig. 2 is a top plan view of the same.

Fig. 3 is an elevation of the inner end 50 of the machine, or the end into which the pieces of work may be fed.

Fig. 4 is an opposite end elevation.

Fig. 5 is a detail view in elevation of one

of the chisel or toolholders, showing in section the support for the same.

55

Fig. 6 is a vertical section through the same.

Fig. 7 is a transverse section taken on the line 7—7 of Fig. 5.

Fig. 8 is a transverse section through the 60 delivery end of the feeder, taken substantially on the line 8—8 of Fig. 2 and showing the adjustable gate for controlling the passage of work to the bed plate of the machine.

Fig. 9 is a detail view in side elevation of 65 the holder for the tension spring adapted to engage the work.

Fig. 10 is an inner end view of the same.

Fig. 11 is a detail top plan view of the 70 trough adapted to be attached to the feeder for supplying pieces of work thereto from an adjacent machine.

Fig. 12 is an inner end view of the trough.

Referring to these drawings, wherein like 75 parts are designated by similar characters of reference throughout the several views, 10 and 11 designate a pair of opposite end uprights adapted to be secured to the floor or the like and which are reinforced by longitudinal brace bars 12. At one side of the 80 machine, which may be termed the rear side thereof, the standards 11 and 12 are provided with a pair of bearings 13 receiving therethrough the opposite ends of a shaft 14, the latter having upon one end immediately adjacent the outer side of the standard 11, a relatively large spur gear wheel 14', and having upon its opposite end exteriorly 85 of the standard 10, a relatively large disk 15.

The shaft 14 is rotated by a pinion 16 90 which is relatively small, and which is mounted on the inner end of a drive shaft 17. The drive shaft 17 is journaled at opposite ends in bearings 18 which are mounted on the standards 10 and 11, and which is provided near the outer end of the frame, with a fixed pulley 19 and a loose pulley 20 adapted to receive a drive belt or the like thereover for controlling the operation of the machine. The shaft 17 is held from 100 longitudinal movement through the bearings 18 by collars 21 which engage against the inner bearing 18 and against the inner side of the pulley 20 respectively. The shaft 14 is also held against longitudinal displacement by means of collars 22 which are 105

mounted upon the shaft 14 adjacent the bearings 13. A belt 23 is employed for transmitting power from the shaft 17 to the shaft 26, and passes over pulleys 24 and 5 25 mounted respectively on said shafts.

The shaft 26 is mounted near the forward portion of the machine in bearings 27 and is employed to operate the feeder which will be subsequently described.

10 Two wrist pins 32 mounted on the outer faces of the gear 14' and disk 15 respectively are connected by pitman rods 30 to, and operate the tool carrying beam 29 sliding on bearing surfaces 28 on the upper 15 edges of the end pieces 10 and 11.

The tool beam 29 is provided in its forward edge with a longitudinally extending undercut groove preferably T-shape in cross-section as indicated at 33. One or more tool 20 holders, are adjustably secured against the forward edge of the beam 29, and each comprises a bracket plate 34 having a rib 35 extending across its rear face adapted to fit 25 partly in the groove 33 to hold the plate 34 from turning upon the beam 29. A clamping bolt 36 whose head fits the T-slot 33 engages each bracket plate near one of its ends and holds it adjustably upon the tool beam 29. The bracket plate 34 is provided in its 30 outer face with a vertically extending dovetailed slot 38 receiving the inner end of a correspondingly formed tool socket 39 vertically adjustable upon the bracket plate by an adjusting screw 41 having a handle 42 35 and swiveled in the overhanging arm 40. A suitable mortising or franking tool 43, of any desired form, is fitted in the tool socket 39 and held in position by means of a set screw 44.

40 The forward side of the frame is provided with a bed plate 45 upon which the work is supported during the advancement of the tool 43 therein. Slidable over the upper face, and at the forward edge portion of the bed plate 45 is a supporting bar or member 46 against which the work is adapted to rest during the impact of the tool 43 thereagainst. The bar 46 is connected at opposite ends to a pair of adjusting screws 47 45 which are swiveled at their outer ends in upstanding bracket arms 48 carried upon the end members 10 and 11. The outer ends of the screw 47 are provided with hand wheels 49, and the screws 47 are connected for simultaneous rotation by sprocket wheels 50 over which is trained a sprocket chain 51. The bar 46 may thus be adjusted from either end of the machine by merely turning the adjacent hand wheel 49.

60 The feeder comprises a bracket frame 52 which is secured to the inner frame portion 11 and extends in longitudinal alinement with the bed plate 45. The upper side of the feeder frame 52 is relatively flat and is adapted to receive the pieces of wood there-

on. The pieces of work may be packed upon the feeder frame or table 52, and held in superposed relation by upstanding side pieces 53 adjustably mounted upon the frame 52 by bolts 54, as shown particularly 70 in Fig. 2. The table 52 is provided at its opposite side with upstanding guard fingers 55 which are preferably permanently secured in place. An upstanding retaining finger 56 may also be mounted across the outer end of the table 52 for holding the pieces of work from longitudinal movement from the outer end of the feeder. A conveyer chain 58 is arranged with its upper portion engaged in a longitudinally extending slot or depression in the upper side of the feed table 52, as indicated at 57 in Fig. 8 the chain 58 being trained over sprocket wheels 59 and 60 arranged respectively in the inner end of the main frame and the remote end of the feed table 52. As shown in Fig. 8, the lower portion of the conveyer chain 58 is free to return through the slot 61 formed longitudinally in the lower portion of the frame 52. The sprocket wheel 59 is 90 carried upon a short shaft 62 which is journaled in a bracket 63 mounted upon the inner side of the frame member 11, and which is provided with a bevel gear wheel 64 meshing with a bevel gear wheel 65 mounted 95 upon the adjacent end of the shaft 26.

The conveyer chain 58 is provided, at one portion thereof, with an outstanding lug 66 of sufficient height to engage the lower edge portion of a piece of work and advance the 100 same longitudinally through the guard fingers 53 and 55, and onto the bed plate 45. To limit the feeding of the work to the bed plate 45, one piece at a time, adjustable gate 67 is employed, the same being in the form 105 of a flat plate having at one lateral edge portion a depending longitudinally slotted arm 68 through which cap screws 69 or the like engage, and which are removably secured in one side of the feeder frame 52. 110 The plate 67 may thus be raised and lowered to accommodate pieces of material of various sizes, and also to admit the pieces of material one at a time beneath the lower edge of the plate 67. After a stack of pieces 115 of work is placed upon the table 52, the lug 66 may remove the lowermost piece of work, and plate 67 prevents the superposed pieces from following and admits the dropping of the stack as soon as the lowermost piece of 120 wood passes through the opening beneath the plate 67.

When a piece of work is slid endwise onto the table 45, the same is held between the bar 46, which serves as an abutment, and two or more retainers 70 which may be in the form of pin supported rollers 71, and which are adjustable longitudinally in the inner edge of the bed plate 45 by engagement 125 in any one of the openings 72. The work 130

is held from upward displacement from the bed plate 45 by means of spring tension, the same being accomplished by the provision of a leaf spring 73 having a relatively flat shank portion engaging in the longitudinal slot 74 formed in one end of a bolt 75, said end of the bolt being externally threaded and provided with a binding nut 76 adapted to be tightened up against the adjacent edge portion of the spring 73. The opposite end of the bolt 75 is engaged in registering recesses formed in the inner opposite faces of a pair of clamping plates 77 and 78 which are held together, and to the upper face of the bar 46 by a cap screw 79 or the like. The upper plate 78 is provided at one end portion with a lug or projection 80 extending toward and engaging the adjacent face of the opposite plate 77 to slightly space the plates 77 and 78 apart and effect a clamping action of the plates 77 and 78 upon the bolt 75.

In Figs. 11 and 12 there is shown a form of trough which may be applied to the feeder for conveying pieces of work thereto from an adjacent machine which performs work upon the pieces prior to the franking of the same. One type of machine which may be used in conjunction with the present invention is what is known as a "sticker" or which places a glass mold on the piece of work. These machines are usually supplied with feeding rollers, and the pieces of work may be discharged therefrom into the trough shown in Figs. 11 and 12.

The trough comprises a bottom board 81 provided at preferably its outer edge portions with an upstanding wall 82 which is relatively high, and which is provided at its opposite edge portion with a relatively low upstanding wall 83. The wall 83 is adjustable toward and from the wall 82, and is held in place by bolts 84 and 85 which may pass downwardly through the wall 83 and to the bottom piece 81. The bolt 84 is provided at its upper end with an enlarged head for engagement with the upper edge of the wall 83 to hold the latter in clamped position upon the bottom 81, and the bolt 85 is provided with an overturned binding finger 86 upon its upper end adapted to clamp between the finger 86 and the upper edge of the wall 83, a supporting rod 87 which is adapted to project obliquely into the passage or throat of the trough. The bolts 84 and 85 may be adjusted in the apertures 88 formed through the bottom board 81 to space the lower wall 83 a greater distance from the higher wall 82. The inner end of the rod 87 is preferably curved at substantially right angles to the longitudinal axis of the rod, and is adapted to deflect and hold the work against the fixed wall 82. The wall 82 is provided with an overturning lip or strip 89 which extends horizontally along

the inner side of the wall 82 in vertically spaced relation from the bottom 81. The strip 89 is preferably seated in a longitudinally extending recess in the inner side of the wall 82, and held in position by an adhesive or the like.

In the use of this trough, when the work is delivered thereto one side, which may be termed the outer side, which may be facing the wall 82. The piece of work as delivered to the trough is supported upon the bead or strip 89 and upon the inner end of the rod 87, the latter being adjusted to the desired angle and projecting to the desired extent into the trough. As the piece of work is forced forwardly by a succeeding piece of work, it is slid along the bead 89 until the piece of work passes the inner extremity of the rod 87. At this time, the piece of work, by its weight, falls from the bead 89 and turns over to present its outer side upwardly, and rests upon the bottom 81. In this position, the piece of work is fed to the feeding mechanism of the machine.

When the trough of Figs. 11 and 12 is employed, the end retaining member 56 is removed from the feeding table 52, and the piece of work slides into position upon the feed table 52 between the upstanding fingers 53 and 55.

The conveyer chain 58 is operated by the rotation of the shaft 26. The lug 66 of the conveyer chain 58 is brought into engagement against the inner end of the piece of work, and forces the latter beneath the gate 67 onto the bed plate 45. The piece of work is slid between the tension spring 73, and is held by the spring yieldingly against the bed plate 45, and from lifting upwardly therefrom.

The mechanism is so timed that as soon as a piece of work is deposited upon the bed plate 45 and the lug 66 of the conveyer chain passes downwardly through the inner end of the bed plate, the tool beam 29 is advanced forwardly. The tool beam 29 is provided near its inner end, and above the sprocket wheel 59, with a stop finger 90 carried upon the forward edge of the beam 29 in the manner of mounting the bracket plate 34 of the tool support. The stop finger 90 is of greater length than the length of the tools 43 and is adapted to project into the path of the work to prevent the subsequent feeding of a second piece of work onto the bed plate 45 during the franking of the piece of work already deposited thereon. The finger 90 is adapted to engage the forward end of the second piece of work and hold the same from advancing onto the bed plate, the lug 66 engaging the inner end of the second piece of work holds the conveyer chain 58 from movement and the pulley 24 is arrested in motion and the belt 23 slides thereover. As the beam 29 is further advanced, the

tools 43, which may be of any desired number, and adjusted in any required position, are advanced against the piece of work, and the work is held from forward displacement by the bar 46. When the tools 43 are advanced against the work, such as a sash stile, the tools are forced into the work and cut or punch the same and compress the material to form the mortise or depression required.

10 The tools 43 are preferably of the fish-tail type so as to form a clean cut at the outer marginal edge of the opening and to compress the material in the mortise by drawing the major portions together rather than expanding and splitting the material, thus preventing injury to the piece of work. The bar 46 may be adjusted by turning the screws 47 to accommodate pieces of work of various widths. The spring 73 is of sufficient strength to hold the work to the table 45 and from moving out of line with the tools 43.

As soon as the tools 43 have completed their operation, the continued rotation of the shaft 14 retracts the tool beam 29 and frees the piece of work. As the finger 90 is now retracted from the path of the work, the conveyer 58 may now operate to advance the second strip of material onto the bed plate 45, and the same steps are carried out in operating upon the second piece of work. By placing the belt 23 between the drive shaft 17 and the feeder shaft 26, the latter may be arrested in its motion by the finger 90, and the drive shaft 17 continued in its motion to operate the tool beam 29.

It is of course understood that various changes and modifications may be made in the details of construction, and the design of the various parts of the above specifically described embodiment without departing from the spirit of this invention, such changes and modifications being restricted only by the scope of the following claims.

45 I claim:—

1. In a woodworking machine, the combination of a bed plate adapted to support a piece of work, a tool beam arranged along one side of the bed plate, means for advancing and retracting the tool beam with respect to the bed plate, the tool beam having a longitudinal slot in its outer edge, a plurality of bracket plates slidably engaging against said forward edge and having tongues adapted to project into said slot, clamping bolts carried by the bracket plate and having enlarged heads engaging in the slot to bind therein and hold the bracket plates in adjusted position, said bracket plates having undercut recesses therein extending at right angles to the groove in said tool beam, tool sockets mounted on said bracket plate and having enlarged inner ends adapted for binding engagement in said undercut recesses, and means carried by the

bracket plates for adjusting said tool sockets in the recesses of the latter.

2. In a woodworking machine, the combination of a bed plate adapted to support a piece of work, a tool beam movable toward and from the said plate, bracket plates adjustably mounted upon the tool beams for moving longitudinally thereof and toward and from each other, tool sockets adjustably mounted in the bracket plates and adapted for movement in paths extending at right angles to the movement of the tool beams, and means for securing tools in said sockets.

3. In a woodworking machine, the combination of a bed plate adapted to support a piece of work, a tool beam, means for advancing and retracting the tool beam with respect to the said bed plate, and a plurality of adjustable and removable tool supports on the beam, each of said tool supports comprising a longitudinally adjustable bracket plate detachably mounted upon the tool beam, and a vertically adjustable tool socket mounted upon the bracket plate.

4. In a woodworking machine, the combination of a bed plate, means for feeding pieces of work endwise upon the bed plate, operating means for the feeding means yieldably connected thereto, a tool support, means for advancing the tool support toward the work on the bed plate, and a stop finger carried by the tool support and movable thereby into position in the path of the succeeding work to arrest the motion of said feeding means during the operation of said tool support.

5. In a woodworking machine, the combination of a bed plate, work feeding means adapted to intermittently position work on the bed plate, a tool carrier, operating means for the tool carrier for advancing the latter toward and from the work on the bed plate, operating means yieldably connected to said feeding means for continuously actuating the latter, and mechanisms controlled by the operation of said tool beam and independent of the feeding means for intermittently checking the feeding of the work to the bed plate when said tool beam is advanced toward the work.

6. In a woodworking machine, the combination of a bed plate, means for feeding pieces of material in an endwise direction upon the bed plate, operating means yieldably connected to said feeding means, a tool support, means for actuating the tool support to advance the latter toward the work on the bed plate, and means carried by the tool support for movement into the path of the work to arrest the feeding of subsequent work upon the bed plates during the operation of the tool support.

7. In a woodworking machine, the combination of a bed plate, a feed table arranged at one end of the bed plate, and end-

less conveyer having its upper portion in the plane of the upper surface of the feed table, a lug projecting from said conveyer, means for supporting and guiding work upon the upper face of the feed table and in the path of said lug, said lug being adapted to engage the outer end of the work and move the latter in an endwise direction onto the bed plate, a tool support, means for advancing the tool support toward and from the bed plate, means for yieldably operating said conveyer chain, and a stop finger mounted on said tool support adapted to be moved thereby into the path of the work upon the deposit of a piece of work on the bed plate, said stop finger being adapted to engage the forward end of the next succeeding piece of work to hold the latter from movement onto the bed plate and to yieldingly hold the conveyer inoperative.

8. In a woodworking machine, the combination of a bed plate, a feed table mounted at one end of the bed plate, an endless conveyer extending across the feed plate and over the adjacent end of the bed plate, a lug outstanding from the conveyer, means for yieldably operating the conveyer to engage the lug with pieces of work and advance the same in an endwise direction onto the bed plate, a tool support, means for advancing the tool support toward the bed plate, and a stop finger mounted on the tool support in the path of the work for interrupting the feeding thereof during the operation of the tools upon the work.

9. In a woodworking machine, the combination of a frame, a bed plate mounted on the frame, a feeding mechanism at one end

of the bed plate, an operating shaft in the frame connected to the feeding mechanism, 40 a drive shaft in the frame, pulleys on the drive and operating shaft, a belt trained over said pulleys and adapted to yieldingly drive the feeding shaft, a countershaft in the frame, a tool beam slidably mounted on 45 the top of the frame, connecting rods pivoted upon the opposite ends of the tool beam and having eccentric connection to said countershaft for advancing and retracting the tool beam with respect to said bed plate, 50 tool supports mounted on said beam, and a stopping device connected to said beam and actuated thereby to arrest the motion of said feeding mechanism during the operation of the tools upon a piece of work. 55

10. In a woodworking machine, the combination of a bed plate, means for feeding work to the bed plate, a tool beam, means for reciprocating the tool beam toward and from the work plate, a bracket plate longitudinally adjustable upon the tool beam, means for clamping the bracket plate in adjusted position upon the tool beam, said bracket plate having a dove-tailed vertically extending recess in its outer face, a tool 60 socket provided with a dove-tailed inner end slidably fitting in said recess, said bracket plate having an overhanging arm in vertical alinement with the recess, and an elongated screw swiveled at its upper end in the arm 65 and engaging in threaded relation through said tool socket, said screw being adapted to be rotated for raising and lowering the tool socket to adjust the same to the work. 70

ARTHUR J. SHIRCLIFFE.
